Primary Examiner — Natasha Vujcic(74) *Attorney, Agent, or Firm* — Winston Hsu(57) **CLAIM**

The ornamental design for a shop lights, as shown and described.

DESCRIPTION

FIG. 1 is a perspective view of a shop lights showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The break lines in the drawings indicate that the appearance of any portion of the shop lights between the break lines forms no part of the claimed design.
